(57) **CLAIM**

The ornamental design for a huber safety needle, as shown and described.

DESCRIPTION

FIG. 1 illustrates an enlarged perspective view of a huber safety needle showing our new design;

FIG. 2 is a rear elevational view thereof;

FIG. 3 is a front elevational view thereof;

FIG. 4 is a top plan view thereof;

FIG. 5 is a bottom plan view thereof; and,

FIG. 6 is a left side elevational view thereof, the right side being a mirror image.

Broken lines are for illustrating unclaimed portions of the article and form no part of the claimed design.
